M. D. FELLOWS

LINGERIE CLASP

Filed Oct. 20, 1924

FIG. 1

FIG. 2

FIG. 3

MARThA DEE FELLOWS,
INVENTOR,
By Oliver D. Barnum,
ATTORNEY.

UNITED STATES PATENT OFFICE.

MARTHA DEE FELLOWS, OF SOUTH PASADENA, CALIFORNIA.

LINGERIE CLASP.

Application filed October 20, 1924. Serial No. 744,719.

To all whom it may concern:

Be it known that I, MARTHA DEE FELLOWS, a citizen of the United States, and a resident of the city of South Pasadena, 5 county of Los Angeles, and State of California, have invented new and useful Improvements in Lingerie Clasps, of which the following is a specification.

My invention pertains to a lingerie clasp 10 adapted to hold together the shoulder straps of ladies' undergarments upon the shoulder, and by means of an auxiliary ball and socket snap member sewed on the outer garment, to maintain the clasp in proper position at 15 all times.

As is well known, much annoyance results from slipping of the ordinary clasp with its contained straps from the shoulder down onto the arm, and to prevent this I 20 have invented the novel device hereinafter set forth.

Its objects are to provide a clasp of simple and inexpensive type that will securely hold the two or more shoulder straps of as 25 many undergarments together and to quickly and easily attach such a clasp to the under side of the outer garment in such a manner that it may be readily detached when necessary. To accomplish these objects I have designed a clasp of a novel type, and an auxiliary strip of metal adapted to 30 be sewed on the under side of an outer garment and removably fixed to the clasp by means of multiple snaps. By such a combination the clasp may be detached from the auxiliary member at will, or may be opened to allow the shoulder straps to be drawn out while still held fast by the snaps to the outer garment. Or, the clasp may be detached from the auxiliary member and other auxiliary members provided on other outer 35 garments be snapped into the clasp.

The construction and operation of my invention will be readily understood by examination of the accompanying drawings, in which

Figure 1 is a side view of my clasp in open position, and shows an auxiliary member adapted to be attached to the clasp by means of snap fasteners.

Figure 2 is a similar view to that of Figure 1, with the clasp in closed position and auxiliary member attached thereto.

Figure 3 is a plan view of the top arm of the clasp in the direction of the arrow 55 shown in Figure 2.

Referring more particularly to the drawings in which similar numerals indicate identical parts in all of the figures:

1 indicates the clasp proper, formed of 60 flat metal stock and bent U shaped to afford approximation of the ends thereof for clasping purposes.

1^a—1^b indicate the upper and lower arms 65 respectively of clasp 1.

2 indicates the outer end of arm 1^b, formed to provide an upwardly projecting loop; 5 indicates a longitudinal cut in the distal end of arm 1^a to provide two lips, 3—4, formed to engage loop 2 on either side in 70 clasping action;

6—6 indicate perforations through member 1^a adapted to receive spherical knobs 8—8 of auxiliary member 7;

7 indicates an auxiliary member adapted 75 to be sewed to the under side of an outer garment, and is provided with multiple projecting spherical knobs 8—8 for snapping action into perforations 6—6 of member 1^a, and further provided with multiple perforations 9—9 adapted for sewing member 7 80 onto a garment;

10—10 indicate resilient tongues, cut longitudinally in arm 1^a and variously directed, the same being adapted to receive knobs 85 8—8 between their crescentically formed ends in snapping action.

Auxiliary member 7 is sewed on the under side of the outer garment, and after clasp 1 is clasped about the shoulder straps, member 7 is placed in alinement therewith and knobs 8—8 pressed into perforations 6—6, thus affording a removable attachment by reason of the resiliency of tongues 10—10. 90

It will be noted that any number of outer 95 garments may be equipped with these auxiliary members, 7—7, all adapted to coincide and fit into arm 1^a, and that when attached thereto clasp 1 must necessarily be held in the desired position on the shoulder, without danger of slipping in either forward, backward or lateral direction.

My clasping means for holding distal ends of arms 1^a—1^b in closed position is particularly novel and strong. Arm 1^a is slit longitudinally at its end, 5, to provide two lips 100

of equal width, 3—4. One of these lips, 3, is bent forwardly and downwardly to engage the outer surface of loop 2 of arm 1^b; while the other lip, 4, is bent downwardly and backwardly in reversed S shape to engage the inner surface of said loop 2.

This double acting clasping means has special novel and useful advantages over any known to the inventor. It is more positive in action because bending of either arm 1^a or 1^b could not destroy the strength of clasping action, since weakening of friction of lip 3 on loop 2, for instance, would automatically increase friction of lip 4 on loop 2, and vice versa. To break the catch, however, it is but necessary to press the finger between arms 1^a—1^b near the distal ends thereof, whereon resiliency of lips 3 and 4 will readily allow detachment of one arm 20 from the other.

Having thus disclosed my invention I claim as new and desire to obtain Letters Patent of the United States upon claims

1. A clasp of the character disclosed 25 struck from flat metal stock and formed U shaped to provide two approximately parallel arms, the lower of said arms terminating in an upwardly projecting loop, the upper arm being slit longitudinally to provide two lips at the distal end thereof; one of said lips being bent to engage the outer curvature of said loop, the other lip bent to engage the rearward or inner curvature of said loop, said lips being adapted to coact 35 with said loop in clasping action.

2. A lingerie clasp of the character disclosed, comprising a U shaped body struck from flat metal stock, the free ends thereof adapted to coact in clasping action; one arm 40 of said body being provided with multiple sockets by means of resilient tongues struck in the body thereof; and an auxiliary member provided with multiple projections adapted to coact with said sockets in removable snapping action.

3. A lingerie clasp of the character dis-

closed, struck from flat metal stock and bent U shaped to provide an upper and a lower arm, the free ends of said arms being provided with releasable clasping means; the upper arm being provided with multiple tongues cut longitudinally therein and formed crescentically at their free ends to constitute a resilient socket between any opposed pair of the same; said sockets being 55 adapted to receive spherical knobs in snapping action; and an auxiliary member adapted to be sewn on a garment and provided with projecting spherical knobs adapted to coact with said sockets in snapping action.

4. A lingerie clasp of the character disclosed, comprising a U shaped metal body with two approximately parallel arms, one of said arms being formed at its end into an 60 upwardly projecting loop; the other arm being slit longitudinally at its free end to provide two lips, one of the same being bent to engage the outward curvature of said loop, the other lip being bent to engage the inward curvature of said loop, said lips coacting in clasping engagement with said loop; the upper arm of said body being further provided with multiple tongues cut longitudinally therein and variously directed, the same being crescentically formed at their free ends to provide a resilient socket between any opposing pair thereof, said sockets being adapted to receive spherical knobs in snapping action; and an auxiliary member adapted to be sewn upon a garment and provided with multiple projecting spherical knobs adapted to fit into said sockets and coact therewith in snapping action.

In testimony whereof, I have signed my 85 name to this application and power of attorney in the presence of two subscribing witnesses.

MARTHA DEE FELLOWS.
